EXTENSIBLE ROLLER SCREEN AND
HOUSING THEREFOR

Pauline K. Nimkoff, Brooklyn, N. Y.

Application December 7, 1950, Serial No. 199,627

5 Claims. (Cl. 160—24)

1

This invention relates to screens of the roller type designed primarily, although not exclusively, for use in small apartments when space is at a premium and wherein it is frequently desirable to shut off a section of a room for reasons of privacy.

An important object of the present invention is to provide a novel roller screen assembly wherein the entire apparatus is completely enclosed in a housing when not in use, the housing occupying very little space and being unobtrusive in appearance and which may blend in with other fixtures in the room.

Another object of the invention is to provide a screen and housing therefore which, although a permanent fixture, can nevertheless be installed with a minimum of expense, or it can be installed by the owner if he possesses even the most elementary knowledge of tools.

A further object of the invention is to provide a novel roller screen wherein the roller is journaled on a vertical axis in a vertical housing of small cross-sectional dimensions and formed with a cover hinged adjacent the floor, the cover completely obscuring the screen from view when not in use but which may readily let down to the floor to form a floor board when the screen is to be extended. Associated with the floor board is a hinged screen supporting part which may be set up in a vertical position to securely hold the screen in extended position against the tension of the spring in the roller.

Fig. 1 is a front elevation of the improved screen in extended position;

Fig. 2 is a plan view thereof, partly in section, the part in section being on line 2—2 of Fig. 1;

Fig. 3 is a front elevation, partly in section of the housing and the posts when in fully closed position;

Fig. 4 is a section on line 4—4 of Fig. 3, on an enlarged scale;

Fig. 5 is a front elevation showing a modified form of the invention.

An embodiment of the present invention may include a flexible curtain 10 mounted on a roller 11 which is mounted for rotative movement in a housing 12. The housing may be made from any suitable sheet material such as plywood, plastic sheets or sheet metal and includes side walls 13, 14 and 15, a base wall 16 and a top wall 17.

At its outer end the curtain is provided with a reinforcing strip 20 and for the purpose of limiting the winding of the curtain on the roller, guides 21 and 22 may extend downwardly from the top wall and upwardly from the base wall, the guides 21 being affixed to the side wall 13.

2

The roller may be of the type usually employed for window shades and is provided with an internal spring 19 which is always under sufficient torsion to completely wind the shade or the roller. It is further provided with a shaft whose terminals 23 are received in fittings secured to the top and base walls, one of such terminals being flattened to prevent rotation between the shaft and the fitting.

10 The housing is further provided with a fourth side wall 25 which forms a closure therefor when the curtain is rolled on the roller, and which is hinged at 26 to the base wall and forms a floor board when in open position. At its outer end 15 the floor board is provided with a block 27 to space it uniformly from the floor when in the open position of Fig. 1.

The curtain is supported in extended position by a post 30 which is hinged at 31 in a bracket on 20 the floor board and is maintained in its upright position by a brace 32 hinged to the post at 33. The opposite end of the brace is cut away diagonally at 34 and is received in a U-shaped socket or stop 35.

25 Suitable securing means for the curtain may include plural pins 36 on the post and loops 37 secured to the reinforcing strip.

Post 30 is shown as being of the full height of 30 the curtain but it may be of lesser height. It may obviously be of shorter length if desired. The post is formed with a recess 40 to receive brace 32 and both members are notched at 41 so as to clear stop 35 when the parts are folded.

The housing is preferably secured directly to 35 one wall of a room and when not in use the parts are in the position of Fig. 3. To use the screen it is only necessary to lay floor board 25 out, erect post 30, fit brace 32 into its socket, extend the curtain and connect it to the post.

40 In the modified form of the invention shown in Fig. 5 the housing 50 may be substantially the same as that shown in Fig. 1 but in this instance the floor board is formed in two sections 51 and 52, the first section being hinged at 53 to the 45 housing and the second being hinged at 54 to the first section. The post 55 is hinged at 56 to the outer end of the second floor board section and a brace 57 retains the post in vertical position. The screen 58 is secured at 59 to the post.

50 While two forms or embodiments of the invention have been shown and described herein for illustrative purposes, and the construction and arrangement incidental to two specific applications thereof have been disclosed and discussed in detail, it is to be understood that the invention is limited neither to the mere details or

relative arrangement of parts, nor to its specific embodiments shown herein, but that extensive deviations from the illustrated forms or embodiments of the invention may be made without departing from the principles thereof.

I claim:

1. The combination of an extensible screen carried on a spring driven roller mounted on a vertical axis and a support for the roller including a housing for the screen when in closed position, the housing being attachable to a vertical member and including top and bottom walls provided with bearings for the terminals of the roller, fixed side walls and a movable side wall attached to the housing at its lower end and providing a floor board when the screen is in extended position, a post hinged at the outer end of the floor board and a bracing means for retaining the post in vertical position, and means for attaching the free end of the screen to the post.

2. The combination of an extensible roller screen mounted on a vertical axis and a support for the roller including a housing for the screen when in closed position, the housing including top and bottom walls provided with bearings for the terminals of the roller, fixed side walls and a movable side wall hinged at its lower end to the bottom wall and providing a floor board when the screen is in extended position, a post hinged at the outer end of the floor board and a bracing means for retaining the post in vertical position, and means for attaching the free end of the screen to the post.

3. The combination of an extensible roller screen mounted on a vertical axis and a support for the roller including an upright housing for the screen when in closed position, the housing being attachable to a vertical member and including top and bottom walls provided with bearings for the terminals of the roller, fixed side walls and a movable side wall hinged at its lower end to the bottom wall and providing a floor board when the screen is in extended position, a post hinged at the outer end of the floor board and a brace hinged at one end thereof to the

post for retaining the post in vertical position, a stop on the floor board which receives the free end of the brace, and means for attaching the free end of the screen to the post.

5. The combination of an extensible roller screen mounted on a vertical axis and a support for the roller including a housing for the screen when in closed position, the housing being attachable to a vertical member and including top and bottom walls provided with bearings for the terminals of the roller, fixed side walls and an extensible, movable side wall attached at its lower end to the bottom wall and providing a floor board which underlies the screen when the 10 same is in extended position, a post hinged at the outer end of the floor board and a brace for retaining the post in vertical position, and means for attaching the free end of the screen to the post.
- 15 20 5. The combination of an extensible roller screen mounted on a vertical axis and a support for the roller including an upright housing for the screen when in closed position, said housing including top and bottom walls provided with 25 bearings for the terminals of the roller, fixed side walls and a movable side wall formed in plural interconnected sections, such side wall being attached at one end thereof to the lower end of the housing and being swingable downwardly from the housing to provide a floor board underlying the screen when the latter is in extended 30 position, a post hinged at the outer end of the floor board and a brace for retaining the post in vertical position, and means for attaching the 35 free end of the screen to the post.

PAULINE K. NIMKOFF.
